U.S. 1937

John H. Knapp, of New York, N.Y.
Letters Patent No. 7987-Dated April 19, 1864.
Design for a Tooth-pick.

The schedule referred to in these Letters Patent and, making part of the same.

To all whom it may concern:

Be it known that I, John H. Knapp, of the City, County and State of New York, have invented a new and ornamental Design for a Tooth-Pick; and I do hereby declare that the following is a full, clear and exact description of the same, reference being had to the annexed drawing, making a part of this specification, said drawing being an elevation of a tooth pick showing my design.

The case A. of my tooth pick is made in the form of a cannon, from the muzzle of which a round stem B. projects, which forms the socket for the spear-shaped tooth pick C. The breech of the cannon A. terminates in a ball a. which joins the barrel by an ogue b. and the barrel is ornamented by a large bead c. having two small beads d. one on each side. Said beads are separated from each other by fillets e.

That portion of the barrel to which in ordinary can-
nons the trunnions are attached, is ornamented by a large bead f. and
two small beads g. one on each side of the large bead, and separated
from the same by fillets h. similar to the beads c and d. at the breech.

The muzzle of the cannon is further ornamented by a
bead i. which is separated by a scotia j. from a small bead k. that
finally joins the plain portion of the barrel by a fillet l.

2

DES. 1937

The entire case with the tooth pick is made of gold, or other metal and plated with gold, and the tooth pick is so arranged that it can be screwed in and out, and that it can conveniently be carried in the pocket.

What I claim as new and desire to secure by Letters Patent is the design for a tooth pick case as shown and described.
